UNITED STATES PATENT OFFICE.

FREDERIC AUMONIER, OF LONDON, ENGLAND.

DESIGN FOR WALL-PAPER.

SPECIFICATION forming part of Design No. 22,961, dated December 12, 1893.

Application filed November 6, 1893. Serial No. 490,211. Term of patent 3½ years. Registered in England March 3, 1893, No. 208,525.

To all whom it may concern:

Be it known that I, FREDERIC AUMONIER, (trading as WM. WOOLLAMS & CO.,) a subject of the Queen of Great Britain, and a resident of 110 High Street, near Manchester Square, London, England, have invented a new and original Design for Wall-Paper, (registered in Great Britain on the 3d of March, 1893, No. 208,525,) of which the following is a specification.

This design for wall paper as illustrated by the accompanying drawing consists of hollyhock flowers and leaves in clusters branching

from a stem the stem being arranged in wavy formation vertically. The background is an imitation of figured lace.

I claim—

The design for wall paper as herein shown and described.

The 10th day of March, 1893.

FREDERIC AUMONIER.
